UNITED STATES PATENT OFFICE

HENRICK J. HJORTH, OF WOBURN, MASSACHUSETTS

VALVE WRENCH

Application filed May 28, 1930. Serial No. 456,482.

The subject matter of the present invention is a wrench adapted to be used for opening and closing valves in pipes buried under the ground; for instance, and particularly, 5 those in house connections from street water mains. It is well known that every such house connection contains a valve by means of which the water supply to the house from the main may be turned on or off. Although 10 such pipes are buried, access to the valve is given by way of a tubular housing which embraces the valve and rises to the surface of the ground, preventing the valve from being covered and made inaccessible by filling of 15 the trench in which the pipe was laid. However, a leak sometimes develops in the pipe near the valve and the flow of water from the leak disturbs the adjacent ground. Frequently in such cases the water makes a channel 20 along the pipe in both directions from the leak and flows into the housing, the bottom end of which is provided with wide slots to permit its lower end straddling the pipe. The water thus entering the housing carries 25 sand, gravel, etc. with it and frequently rises to such a height that it deposits a layer or body of dirt directly over the valve, of such thickness and density as to prevent access to the wings or handle of the valve cock by 30 the ordinary socket wrenches provided for use in this class of valves. The common wrench now used for this purpose consists simply of a fork made of two narrow blades parallel to one another on the end of a long 35 rod, the other end of which is provided with a cross bar. It is difficult at best to find the valve cock handle wings with such a wrench, and entirely impossible when the housing is filled at the bottom end with dirt or gravel. 40 So far as I am aware no municipal water departments are equipped with any better tool for operating such valves than the wrenches above described. Hence, when a leak develops which results in thus blocking the 45 housing, it is impossible to turn off the water by means of the wrench and necessary actually to dig a hole in the ground in order to gain access to the valve. Such digging operations are time consuming and costly and 50 may have serious consequences due to the de-

lay occurring before the flow from the leak can be stopped.

It is my object to avoid the difficulties above mentioned by furnishing a wrench which can find its own way through sand and dirt of any depth in the valve housing and will burrow through the dirt and then center itself on the valve handle. The invention consists in such a wrench including the combination of abutments adapted to embrace and apply torque to the valve cock handle, and associated means for cutting through and displacing sand, gravel and similar material which may be deposited over the valve. The characteristics of this invention and the particulars in which it consists are described in the following specification in connection with one specific embodiment thereof.

In the drawings,—

Fig. 1 is a fragmentary sectional elevation 70 showing part of a water connection from a street main to a house, the valve in such connection, the housing surrounding the valve, and a wrench of my invention in position to close the valve;

Fig. 2 is a plan of the wrench head and a section through the same on line 2—2 of Fig. 1;

Fig. 3 is a longitudinal section of the wrench head on line 3—3 of Fig. 2;

Fig. 4 is a cross section on line 4—4 of Fig. 3;

Fig. 5 is a bottom end elevation of the wrench as seen from below the line 5—5 of Fig. 1.

Like reference characters designate the same parts wherever they occur in all the figures.

a represents a pipe typifying any connection from a street water main to an adjoining house, or indeed any pipe which is buried under ground, and *b* is a shut off valve in such pipe. *c* represents conventionally the ordinary housing used in connection with such valves to maintain a clear passage from the surface of the ground for application of a wrench to the valve. Such housings are ordinarily cylindrical tubes having a flange *c'* at the bottom end to rest on a support in the bottom of the trench in which the pipe *a*

is laid and having a displaceable cover at the upper end. It is substantially larger than the valve and large enough in diameter to provide room for two slots d in opposite sides 5 at the lower end by which it is adapted to straddle the pipe at either side of the valve.

The wrench of this invention is embodied in what I have referred to above as the head, which is designated as a whole by the letter 10 H and consists of a number of parts. It comprises a tubular cylindrical shell e and a shank f centrally located therein, the diameter of which is substantially smaller than the internal diameter of the shell, and the 15 lower end of which is connected to the shell at opposite sides by wings or webs g , h . Preferably the shank and wings are beveled to a more or less sharp edge at the lower side or end to facilitate penetration through 20 ground material.

Between one side of the wing g and the adjacent part of the shell, and extending downward beyond the shank and wing is a lug j ; and symmetrically arranged with respect thereto and to the wing h is a similar lug k . These lugs have faces j' , j'' , and k' , k'' , respectively, of which the faces j' , k' are parallel to and on opposite sides of a diameter of the shell, and the faces j'' , k'' are 30 parallel to and on opposite sides of a different diameter of the shell, preferably one at right angles to the first mentioned diameter. This arrangement of the lugs enables them to engage the cross bar or handle 35 wings of the usual valve cock on respectively opposite sides of opposite ends thereof whereby to turn the cock into either open or closed position when the valve is turned one way or the other.

40 An inclined rib or vane l extends from the upper side of the lug j to the upper end of the shell. Its face at the lower end is preferably flush with the face j'' of this lug. A similar rib or vane m leads from the lug k 45 in a similar relation to the face k'' of the latter. These ribs are preferably helical and extend with such a pitch, or helix angle, that they assist in propelling through the annular space between the shank and the shell the 50 material entering the shell when the wrench is forced into sand or the like. These ribs maintain the same angular relation to the circumference of the shell in all transverse planes throughout their length. That is, 55 their transverse elements are not radial to the shell but are tangential to an inner circle concentric with the shell, at least in the construction shown.

The lower edge of the shell is formed with 60 wide serrations or teeth n for the purpose of more readily penetrating into packed sand and dirt, loosening it, and facilitating penetration of the tool through such material.

The upper end of the shank is slotted or 65 forked to provide two jaws o in the space

between which the end of the operating rod p may be placed and secured by pins, bolts, etc. The operating rod may be otherwise like the shank or operator of the ordinary wrench, equipped with a cross bar r on its upper end. Or, alternatively, the wrench head shank 70 may be formed with a single tongue to be embraced between the jaws of a forked end on the operating rod.

The tool head H is preferably made in one 75 piece as a casting of steel or other suitably hard, tough and durable material; although it may be fabricated otherwise without departure from the invention. Its manner of use will be readily understood from the foregoing description; and it will be appreciated that it is adapted to penetrate through closely packed dirt in its descent through the valve housing to a valve in situations such as contemplated here. Great depth of dirt 80 covering the valve is not a serious obstacle, for the driving of the tool into the dirt does not compact it, but rather loosens and stirs it up so that it is able to pass through the wide spaces between the shell and the shank, being 85 assisted thereto by the inclines l and m .

Arrived at the valve, the wrench centers 90 itself on the cross bar of the cock and the lugs j and k are thus placed so that they embrace such cross bar, being then disposed so that they will turn the cock when the wrench is thereafter rotated.

95 Of course this wrench is effective when there is no accumulation of dirt in the housing e as well as the common wrench; but when 100 there is such an accumulation it performs a service which the common wrench cannot do and obviates the slow, laborious and expensive digging heretofore necessary in so many cases where a leak has occurred near the location of the valve.

105 In the foregoing description I have used the term "handle" as a convenient term to describe that part of the valve cock which is provided for turning it, whether by hand or by the agency of a wrench. It is to be understood that such term is merely descriptive and is used without any intent to indicate a limitation of structure or utility of the invention.

110 The lower end of the shank serves as a stop to engage the upper end of the valve plug or its handle and limit descent of the tool at a point such that the teeth on the end of the shell cannot strike and cut or mar the valve body. This stop is above the lugs, whereby 115 it allows them to pass by and embrace the valve handle, but it prevents the wrench from moving down too far.

120 What I claim and desire to secure by Letters Patent is:

1. A wrench comprising a shank, separated lugs connected to the end of said shank and projecting beyond said end adapted to embrace the handle of a valve, and a shell 125

surrounding said shank and connected thereto with an intermediate space for passage of granular material when the wrench is forced endwise into such material.

5 2. A wrench comprising a shank, a coaxial shell surrounding said shank and an intermediate annular space, rigid connections between said shank and shell crossing said intermediate space and having spaces between them, and lugs projecting inward from the opposite sides of the shell adapted to embrace and apply torque to the handle of a valve.

10 3. A valve wrench comprising a shank, a shell surrounding said shank and an intermediate space, and extending at one end beyond the adjacent end of the shank, means crossing said intermediate space and connecting the shank and shell together, lugs 15 projecting inward from opposite sides of the shell adapted to embrace and apply torque to the handle of a valve, and tooth serrations 20 on the protruding end of the shell.

4. A valve wrench comprising a shank, a shell surrounding said shank and connected thereto with an intervening annular space, extending at its lower end beyond the lower end of the shank, means on the lower end of the shell for penetrating and loosening granular material when the shell is thrust endwise into such material and rotated, inclines 25 on the inside of the shell for propelling such material through said intermediate space when the wrench is so rotated, and lugs on 30 the inside of the shell adjacent to its lower end for embracing and applying torque to the handle of a valve.

5. A wrench comprising a tubular shell having teeth at its lower end for boring 35 through sand, etc., and having interior lugs for embracing a valve handle and applying turning force thereto, and a stop between and above said lugs for limiting the movement of the shell toward the valve body after 40 the lugs have so embraced the handle.

In testimony whereof I have affixed my signature.

HENRICK J. HJORTH.
